SAFETY LOCK

Václav Ostadál, Prague, Czechoslovakia

Application January 11, 1949, Serial No. 70,325
In Czechoslovakia October 29, 1948

5 Claims. (Cl. 292—169)

1

For locking the doors of bath-rooms, water-closets and the like use is made at present of door locks constructed in such a manner that by turning the inner handle in reverse direction, usually by an angle of 90 degrees, the person who occupies the room is secured against opening of the door by another person using the outer handle. Further on, the known type of safety locks are used in which by reverse turning of the outer handle it is possible, when required, to unlock the door which has been locked by means of the inner lock and to open the door by depressing the outer handle, while with the inner handle unlocked it is possible, by the said turning movement of the outer handle, to place the lock in such a condition as to make impossible the opening of the door by means of the inner handle. The last mentioned provision makes impossible the access of unauthorised persons e. g. from a bathroom to the interior of the flat, if the window of the bath-room or the like is easily accessible from outside the house.

However, the safety locks of the kind specified are relatively complicated and cumbersome, consist of a large number of component parts, and when a certain degree of wear has taken place they become inefficient.

The safety lock in accordance with the present invention complies reliably and permanently with all the aforementioned requirements and in addition is extremely simple and cheap in respect both of the material used and the room required for mounting the same on a door.

The invention resides in an arrangement in which the bolt of the safety lock is adapted to be controlled and locked independently either by the outer or by the inner handle, the said bolt being provided in its inner extended part with a single aperture in which operates a finger of the tumbler of only one of the two handles while a projection and a stud of the second handle co-operate only with projections on the outer periphery of the said extended portion of the bolt. An important simplification as compared with the prior constructions resides in the fact that the inner part of the bolt is provided with a single aperture, while the known constructions have usually at least two apertures with a tumbler arranged movably in each of the apertures.

Further details and advantages and the operation of the lock in accordance with the present invention will appear from the following description of an embodiment of the same as shown in the drawing, in which

Figure 1 is a view of the lock casing with a side plate of the same removed, and

2

Figure 2 is a cross-sectional view of the lock taken along the line A—A of Figure 1.

The lock in accordance with the present invention has a casing 1 and a front plate 2 mounted on the same, the end of the bolt 3 passing through an opening provided in the plate 2. For opening the door, the bolt 3 is retracted in the direction of the arrow B until the extended inner part 3' of the bolt abuts against the back wall of the casing shown in Figure 1, the bottom of the said inner part engaging and sliding upon a stud 4 fastened in the walls of the casing. A spring 5 urges the bolt towards its extreme right hand position as viewed in Figure 1, i. e. outwardly of the casing to its latched position.

The rearwardly extended plate portion of the bolt 3 is provided with an aperture 6 through which passes a tumbler 7 fastened on a squared shank portion 18a of the upper handle 18, this handle being usually on the outer side of the door leading to the room and usually occupying a horizontal position, as shown, in the latched position of the bolt. The tumbler 7 is provided with a finger 8 movable within the aperture 6, and above the upper face plane of the inner part of the bolt the tumbler is provided with another finger 9, as shown in Figure 1. At nearly diametrically opposite sides with respect to the above mentioned fingers, the tumbler is provided with flat surfaces 7a, 7b which are parallel to the axis of rotation of the tumbler and are engaged in turn by a spring 10. The underside of the inner part 3' of the bolt is engaged by the lower tumbler 11 which is fastened on a squared shank portion 19a of the lower handle 19, this handle being usually the one on the inner side of the door leading to the room and usually occupying a horizontal position, as shown, in the latched position of the bolt. This last mentioned tumbler is provided with two projections 12 and 13, of which the first co-operates with a corresponding portion of the bolt 3 and the second co-operates with the finger 9 of the tumbler 7. The tumbler 11 carries further a stud 14 adapted to co-operate with the bolt. The tumbler 11 is also provided with two flat surfaces 11a, 11b parallel to its axis of rotation and at right angles to each other, with which a spring 15 is adapted to engage in turn.

The drawing shows in full lines the component parts of the lock in the position which they occupy when the door may be opened in the usual way by depressing the outer or the inner handle below its normal horizontal position thereby rotating either the tumbler 7 or tumbler 11 counterclockwise as viewed in Fig. 1. If the

outer handle 18, that is the upper one as shown in the drawing, is depressed, the finger 8 which bears against the left side of the aperture 6 in the bolt inner part 3' will push the bolt to the left as viewed in Figure 1 until its outwardly projecting end portion is withdrawn into the corresponding opening so that the door may be opened. Upon release of the handle the spring 10 will return the tumbler 7 and with the same handle itself to their original position, while the spring 5 will move back the bolt 3.

Similarly, if the inner, that is the lower handle 19 is depressed, the projection 12 of the tumbler 11, which bears against one face of a depending toe portion 17 at the bottom of the bolt 3, will push the bolt to the left as viewed in Figure 1, and when the handle is released again the two members just mentioned are returned to their initial position under the action of the springs 5 and 15.

If a person enters the room and wishes to make impossible the opening of the door in the usual way from the outside, the inner handle 19 should be turned back in clockwise direction as viewed in Fig. 1 from its normal horizontal position to a vertical position. As a consequence, the tumbler 11 will assume the position shown in dot and dash-lines in Figure 1. The stud 14 will assume the position 14' in which it engages in an adjacent recess formed in the opposite face of toe portion 17 of the bolt 3, while the shoulder 16 of the bolt will engage with the stud 4 whereby no further movement of the bolt 3 is possible if the upper handle 18 is depressed. The tumbler 11 is retained in this position by the pressure exerted on its bottom flat face by the spring 15.

If with the lock fixed in the manner just described it is required to open the door from the outside, the outer handle 18 should be turned about 90 degrees clockwise as viewed in Fig. 1 from its normal horizontal position. During the first part of this movement the finger 9 will engage the projection 13 of the tumbler 11, which projection occupies at that moment the position 13' shown in dot and dash-lines in Figure 1, and then the finger 9 during its further movement will cause the tumbler 11 to return to its initial position shown in full lines in Figure 1, the spring 15 also taking part in this operation. Thereupon the door may be opened by the usual movement of the upper handle 18.

On the contrary, when it is desired to lock the door from the outside so as to prevent it being opened by means of the inner lower handle 19, the outer upper handle 18 is brought again to its above mentioned vertical position assuming of course that the lower handle 19 is in its horizontal position. In this case, the finger 8 of the upper tumbler 7 will assume the position 8' shown in dot and dash-lines in Figure 1 in which this finger prevents any movement of the bolt 3 and especially the shifting of the latter due to depression of the lower handle 19. Also when the outer handle 18 has been turned to its upright, locking position, the inner handle 19 and tumbler 11 cannot be rotated clockwise to unlock the bolt for when handle 18 occupies an upright position finger 9 occupies its vertical, broken line position 9' in which the flat underside of the toe portion thereof lies substantially in contact with an adjacent flat face 11c on tumbler 11 thus locking the latter against rotation clockwise. Consequently when the bolt is locked in the latched position by the inner handle 19 it can be unlocked by the outer handle 18 but when so locked by the outer

handle it cannot be unlocked by the inner handle.

The invention is not limited to the embodiment described in the specification and illustrated in the drawing, but this single example shows clearly that the construction of the lock is very simple and that with such a construction it is possible to save much room and material. Thus, very good results were obtained in practice with a lock in which the distance between the axes of the tumblers was as small as 35 millimeters and the largest dimension of the casing was 80 millimeters.

What I claim is:

1. In a safety door lock, the combination comprising; a lock casing; a bolt slidable within said casing; said bolt being normally urged outwardly of said casing towards its latched position and including an apertured plate portion in a rear extension thereof; a first tumbler within said casing mounted for rotation in the apertured portion of said bolt and controlled by a handle on one side of said casing, said tumbler including first and second fingers, said first finger being rotatable into engagement with the inner periphery of the apertured portion thereof, said first finger being engaged with the rear part of said apertured portion upon rotation in one direction to retract said bolt and engaged with the fore part of said apertured portion upon rotation in the opposite direction to lock said bolt in the outward latched position; and a second tumbler within said casing mounted for rotation outside of the outer periphery of the rear extension of said bolt and controlled by a second handle on the opposite side of said casing, said second tumbler including a first portion movable upon rotation of the tumbler in one direction into engagement with a portion of said outer periphery effective to lock said bolt in the outward latched position, a second portion engaging another portion of said outer periphery upon rotation of said second tumbler in the opposite direction to retract said bolt and a third portion offset axially from said first and second portions which when said second tumbler occupies the bolt locking position is engageable by said second finger upon rotation of said first tumbler in the said opposite direction to thereby rotate said second tumbler in the direction to disengage the said first portion thereof from the said outer periphery of the bolt.

2. A safety door lock as defined in claim 1 wherein the said second finger on said first tumbler includes a flat adapted to substantially contact a flat on said second tumbler when said first tumbler is rotated in said opposite direction thereby to prevent rotation of said second tumbler.

3. A safety door lock as defined in claim 2 wherein the said first portion on said second tumbler is constituted by a stud engageable with one face of a depending toe portion on the rear extension of said bolt, and the said second portion on said second tumbler is constituted by a projection engageable with the opposite face of said toe portion.

4. A safety door lock as defined in claim 3 wherein each of said tumblers is provided with a pair of flat faces in parallel relation to the axis of tumbler rotation and substantially at right angles to each other and adapted to co-operate in succession with a spring retaining said tumbler in either of two predetermined positions.

5. A safety door lock as defined in claim 4

and which further includes a fixed stud extending transversely in said casing upon which the underface of the rearward extension of said bolt is seated for sliding movement, said underface including a shouldered portion engageable with said stud and providing a stop for the bolt when the latter has moved a predetermined distance in the forward latching direction.
